UNITED STATES PATENT OFFICE.

JOHN O. MCKEAN, OF WESTFIELD, MASSACHUSETTS, ASSIGNOR TO FOSTER MACHINE COMPANY, OF WESTFIELD, MASSACHUSETTS, A CORPORATION OF MASSACHUSETTS.

DEVICE FOR GUIDING, CLEARING, AND TENSIONING YARN.

Application filed June 9, 1921, Serial No. 476,264. Renewed June 14, 1923.

To all whom it may concern:

Be it known that I, JOHN O. MCKEAN, a citizen of the United States, and resident of Westfield, in the county of Hampden and 5 State of Massachusetts, have invented a new and useful Improvement in Devices for Guiding, Clearing, and Tensioning Yarn, of which the following is a specification.

The object of my invention is to provide 10 certain improvements in the construction, form and arrangement of the several parts of a device for guiding, clearing and tensioning yarn, whereby the life of the device is materially lengthened; in which the parts 15 which are subject to wear may be readily replaced; in which the rotation of the gravity operated disc by the yarn is assured; and in which the removable skeleton yarn support may be adjusted to different positions.

20 This invention relates more particularly to improvements in the device covered by my application filed April 12, 1921, Serial No. 460636.

A practical embodiment of my invention 25 is represented in the accompanying drawings, in which,

Fig. 1 represents the device in top plan.

Fig. 2 represents the same in side elevation.

30 Fig. 3 represents the device in bottom plan.

Fig. 4 represents the same in front elevation.

Fig. 5 represents the device in rear elevation.

35 Fig. 6 represents a section taken in the plane of the line VI—VI of Fig. 1, looking in the direction of the arrows.

The bracket is preferably a casting which 40 comprises an integral resilient yoke, the lower and upper branches of which are denoted by 1 and 2. These branches are provided with lateral extensions 3 and 4 respectively, forming between them a slit 5 for the passage of the yarn.

45 The lateral extension 3 may be provided with a downwardly extended ear 6.

The upper branch 2 is sprung out of its 50 normal position to vary the width of the slit 5 without changing the parallelism of its walls, by means of an adjusting screw, the shank 10 of which passes through the upper branch 2 across the yoke and into screw-threaded engagement with the lower branch 1, the head 11 of which screw is preferably 55 countersunk in a recess 12 in the upper

branch 2. As the device is shown, the screw is arranged to spring the upper branch 2 toward the lower branch 1 of the yoke to narrow the yarn slit 5, the resiliency of the yoke serving to spring the branches apart to 60 widen the slit as the screw is turned back.

The parts hereinabove described serve to act as a very effective and simple yarn clearer or slab catcher, which may be readily adjusted to the minutest degree for different 65 sizes of yarn and then will engage bunches, slubs, knots or other enlarged portions of the yarn for clearing the same.

The bracket may be supported in any suitable manner on the bar 13 of the machine, 70 as for instance by providing the lower branch of the yoke with a hollow lug 14, through which the bar 13 extends; a set screw 15 being provided for securing the bracket on the bar.

An arm 16 projects laterally from the lower branch 1 of the yoke, from which arm projects rearwardly a finger 17 having a hooked-end 18 which serves as a guide and keeper for the yarn as it enters the device. The arm 16 is provided with a depressed portion 19 between the yoke and finger, over which depressed portion the yarn leads to the tension device to be immediately described.

The gravity tension device for the yarn is 85 constructed and arranged as follows:—

A guard portion 21 extends rearwardly from the lateral extension 4 of the upper branch 2 of the bracket. The upper branch is also provided with an overhanging portion 90 23 forming a bridge leading from the rear end of the guard 21 to the front end of the said upper branch.

A split pin extends through the overhanging portion 23 and projects downwardly 95 therefrom to a point below the yarn support to be hereinafter described, which pin is frictionally held in its position so that it may be removed from the overhanging portion when so desired. In the present instance I have shown this pin as a cotter pin, the branches of which are denoted by 24, 25 and the laterally turned head of which is denoted by 26. This laterally turned head end of the pin serves as a convenient handle 100 for manipulating the pin. The bending of the head end of the pin also ensures the keeping of the branches 24, 25 of the pin together when the pin is inserted into its operative position, and does not permit the 110

spreading of the branches as is the tendency where the head end of the pin is not turned laterally.

The overhanging portion 23 is provided

- 5 with an uprising guard 27 for preventing the yarn from being caught on the head 26 of the pin, it being understood that the head of the split pin may be swung laterally into a position in front of the guard for more
10 completely protecting the head of the pin from engagement by the yarn.

The removable skeleton yarn support which forms a part of the tension device for the yarn comprises a substantially U-shaped grid, the branches of which are denoted by 29, 30, and the downwardly inclined closed end of which is denoted by 28. These branches are inserted into holes through the lower branch of the yoke and
15 the skeleton support or grid projects laterally from the said lower branch of the yoke to a point considerably beyond the guard 21, a space 22 being left between the top of the skeleton support and the bottom of
20 the said guard for permitting the introduction of the yarn when threading the same. These branches 29 and 30 of the skeleton support are located in a substantially horizontal plane upon opposite sides of the
25 depending split pin and the skeleton support may be adjusted longitudinally to different positions, a set screw 31 carried by the lower branch of the yoke being arranged in position to engage one of the branches to
30 clamp the skeleton support in its adjusted position against unintentional removal. The said branches may also be flattened along their upper surfaces as shown, if so desired.

The downwardly inclined outer end of the
40 skeleton support preferably extends below the bar 13 when the device is in position thereon, so as to ensure the guiding of the yarn into its proper position in the device.

The weighted disc 32 which forms a part
45 of the tensioning device is loosely mounted on the depending split pin and normally rests upon the removable and adjustable skeleton yarn support. This weighted disc is provided with an auxiliary arranged depending hollow lug 33 which projects below the top of the skeleton yarn support, in the present instance between the branches of the same, in position to be frictionally engaged

by the yarn as it passes between the weighted disc and the yarn support, whereby the disc 55 is rotated, thus providing an even wear on the bottom of the said disc.

It will be seen that as the skeleton yarn support becomes unduly worn at any one point, the screw 31 may be released and the 60 yarn support moved longitudinally to a slight degree and then again clamped in its new adjusted position. By this longitudinal adjustment of the yarn support I am enabled to materially lengthen the life of the 65 support. When all of the surfaces of the yarn support between its limits of adjustment become worn, the yarn support may be removed and it may be replaced by a new yarn support. 70

The parts shown and described, but not claimed herein which relate more particularly to the construction of the yarn clearer or slub catcher form the subject matter of a copending application filed by me on September 16, 1920, Serial No. 410637. 75

It is evident that various changes may be made in the construction, form and arrangement of the several parts without departing from the spirit and scope of my invention; hence I do not wish to limit myself to the particular embodiment herein shown and described, but 80

What I claim is:—

1. In a tension device, a bracket, a substantially U-shaped grid forming a skeleton yarn support projecting laterally from said bracket and adjustable longitudinally therein, and a gravity operated disc arranged to coact with said yarn support, the yarn support being removable and the outer end thereof being inclined downwardly. 85

2. In a tension device, a bracket, a gravity operated disc, a yarn support projecting laterally from the bracket and adjustable longitudinally therein and arranged to coact with said disc, said yarn support comprising a substantially U-shaped grid, the outer end of which is unsupported and inclined downwardly and the branches of 90 which span the space beneath the disc. 100

In testimony, that I claim the foregoing as my invention, I have signed my name this 3rd day of June, 1921.

JOHN O. McKEAN.
